UNITED STATES PATENT OFFICE.

J GROVE BROWN, OF KINGSTON, NEW YORK.

CAR-UNLOADER.

1,345,121.

Specification of Letters Patent. Patented June 29, 1920.

Application filed May 26, 1919. Serial No. 299,976.

To all whom it may concern:

Be it known that I, J GROVE BROWN, a citizen of the United States, residing at Kingston, in the county of Ulster and State 5 of New York, have invented certain new and useful Improvements in Car-Unloaders, of which the following is a specification.

This invention relates to portable apparatus for unloading material from railway 10 cars and loading it into wagons or trucks. The invention is designed particularly for handling broken or crushed stone, used in making roadways, but it is suitable for handling other lump or crushed material.

15 In carrying out the invention, I provide a bin which is supported at its ends on wheeled columns, the columns being spaced apart a sufficient distance to permit a truck or wagon to pass between them, under the 20 bin, so that the contents of the bin may be discharged into the vehicle. Attached to the bin is a folding elevator, which, when in use, extends above the bin and also into a pit dug alongside the railway track to receive and deliver the material into the bin. 25 I also provide a chute adapted to be set into an excavation between the cross-ties of the railway, to receive the material from the car, and a feeder at the lower end of the chute 30 feeds the material in regulated quantities into the buckets of the elevator as they travel upwardly in the pit. By adjusting the feeding device to the speed of the elevator, the unloading of the car and loading 35 of the bin may go on rapidly and continuously, so that the car is not long detained. The trucks or wagons may drive beneath the bin and receive their loads without delay and without interfering with the 40 operation of the elevator.

In the accompanying drawing, which illustrates my invention,

Figure 1 is a side elevation of the unloading apparatus, the elevator being shown in operative position in full lines and in folded 45 positions in dotted lines;

Fig. 2 is a section through the loading bin on the line 2—2 of Fig. 3;

Fig. 3 is a top plan view of the bin, with 50 the side and end doors in open position;

Fig. 4 is a section on the line 4—4 of Fig. 2;

Fig. 5 is a plan view of the detachable 55 reach for connecting the front and rear supporting columns for the bin when the bin is to be moved;

Fig. 6 is a side elevation of the elevator; Fig. 7 is a rear elevation of the same;

Fig. 8 is a detail view showing the manner of supporting the slack portion of the 60 bucket chain when the elevator is folded;

Fig. 9 is a section on the line 9—9 of Fig. 6;

Fig. 10 is a section through the discharge chute and feeder, taken on the line 10—10 65 of Fig. 11, and showing also a portion of the bucket chain arranged within the pit;

Fig. 11 is a view showing the discharge chute and feeder, in elevation, as viewed from left to right in Fig. 10, and, 70

Fig. 12 is a side elevation of the elevator and part of the bin, showing the elevator folded, with certain of the drive chains removed.

Referring to Fig. 1 of the drawing, A 75 indicates a storage bin which is supported at its ends by columns 1 and 2, which columns are carried by front and rear pairs of supporting wheels, 3 and 4, respectively. The columns 1 and 2 are spaced apart a 80 sufficient distance to afford a driveway between them and the bin is supported on the columns at a sufficient height so that a wagon or truck driven through the driveway between the columns will clear the bin. 85

As shown in Figs. 2, 3, and 4, the bin comprises a rectangular frame within which are arranged floor pieces 5, which incline downwardly from the ends of the bin toward the center, forming with the sides 6 90 a hopper. The bottom 7 of the hopper is provided with discharge openings which may be opened and closed by doors 8, the latter being movable by means of rack rods 9, connected to the doors and operable by 95 means of pinions 10, arranged upon vertical shafts 11, which shafts extend downwardly in the forward supporting column and are provided with hand wheels 12, whereby the shafts may be turned and the doors opened 100 and closed. Doors 13 are hinged to the sides of the frame and movable from the horizontal, closed position to the vertical position. Other doors 14 and 15 are secured to the bottom pieces 5 near the ends of the 105 latter, and these doors also fold downwardly to closed position and are movable to the upright positions shown in Figs. 2 and 3.

When the doors 13 and the doors 14 and 15 are in their raised positions, it will be evident that they form upward extensions of the bin. Hooks 16 are provided for con- 110

necting the end doors to the side doors when the doors are in raised position. When it is desired to fold the doors, the doors 14 and 15 are first let down and the doors 13 are then closed over the doors 14 and 15.

The elevator B is supported upon the bin and the frame of the elevator is composed of three sections. The central section f of the frame comprises parallel bars 17 of angle steel, arranged in inclined position at the rear of the bin and having their upper ends 17' bent over into horizontal position and suitably secured to the top of the bin frame. Braces b connect the lower ends of the bars 17 with the column 2. The upper section f' of the elevator frame comprises two parallel bars 18, (Figs. 7, 9 and 12) which are hinged a short distance from their centers to the bars 17 by hinge pins 19, which project from the bars 17 at or near their upper ends and engage ears 20 on the bars 18, as shown in Figs. 6 and 12. This hinged section of the elevator frame may be swung about its pivotal point from the folded position shown in full lines in Fig. 12 and in dotted lines in Fig. 1, to the upright position shown in full lines in the latter figure and in Figs. 6 and 7. The lower section f'' of the elevator frame comprises a pair of parallel bars 21, which are slidable upon the stationary bars 17 of the central section.

A shaft 22 is journaled in suitable bearings upon the lower end of the upper section f' of the frame, and this shaft carries a driving pulley 23 which, when the elevator is in use, is connected by a belt 24 to a motor 25, carried by the rear support 2 of the bin. Upon the shaft 22 is arranged a sprocket wheel 26, (Fig. 7) and this sprocket wheel is connected by a chain 27 to a sprocket wheel 28 on a shaft 29, journaled in the upper end of the section f' . The bucket chain 30 passes over a driving sprocket 31 on the shaft 29 and also around an idle sprocket wheel 32, the latter being journaled upon a shaft 33 at the lower end of the lower section f'' . From this it will be seen that when the motor is in operation the bucket chain will be driven thereby through the medium of the pulley 23 and drive chain 27. A winding drum c is provided on the central section f , and a chain 34 on this drum is adapted to be connected to the lower end of the upper section, as shown in dotted lines in Fig. 12, for the purpose of raising or lowering said section; or to be connected, when the elevator is folded, to a portion of the bucket chain, for supporting the latter, as shown in full lines in Figs. 8 and 12. The winding drum c may be turned by a crank 35, which is secured to the shaft 36, the latter being connected by gears 37 and 38 to the drum c ,

as shown in Fig. 7. When the elevator is folded and it is desired to extend the upper section, the chain 34 is connected to the lower end of said section, as shown in dotted lines in Fig. 12, and by winding the chain 70 upon the drum, the upper section will be caused to rock about the pivots 19 and come into alignment with the fixed section f , and in this position it will be held by the chain. To fold the upper section it is only necessary to unwind the chain from the drum and the weight of the upper portion of the upper section will cause said latter section to assume the horizontal position shown in Figs. 1 and 12. When the upper section has 80 been folded, the chain may be released therefrom and connected to a slack portion of the bucket chain to support the latter, as hereinafter explained.

The central section of the frame is provided with another winding drum d , (Fig. 7) and this is operated by a handle 39, geared to said drum by gears 40—41. A cable 42 on the drum has its ends connected to the upper and lower ends of the section f'' , and it will be evident that by operating the crank 39 the cable will cause the sliding section to move in one direction or the other according to the way the crank is turned. When the section f'' is raised to its upper 95 position, the lower end of the elevator will be well clear of the ground; but said section may be lowered so that its lower end will extend downward below the surface of the ground into a pit e . When the lower section 100 is raised, it will be evident that a considerable slack will occur in the bucket chain and it is necessary to provide means for supporting this slack portion when the elevator is folded for transportation. For this purpose, after 105 the upper section has been lowered to its horizontal position by unwinding the chain 34 from the drum c , said chain may be detached from the upper section and connected to cross pins on the bucket chain, as 110 shown in Fig. 8, said chain being provided with hooks 43 for that purpose. Then, upon turning the crank 35 the slack portion of the bucket chain may be raised and supported in loop-form, as shown in Fig. 12 115 and in dotted lines in Fig. 1.

When the bin and elevator are to be moved, a detachable reach r , illustrated in Fig. 5, is connected between the front and rear supports for the bin, as indicated in 120 dotted lines in Fig. 1, so that the pull on the rear column is exerted through the reach and not through the bin. A shaft 44 is shown connected to the front axle and the machine may be moved from place to place 125 by horses or by connecting the same to a motor vehicle or tractor.

In Fig. 1 of the drawing, the elevator is shown in its working position with relation to the railway car which is to be unloaded, 130

the body of the car being represented at 45, and one of the car axles at 46. Below the car is shown a delivery chute G for receiving the stone or other material from the 5 car and delivering it to the bucket chain of the elevator in the pit e. This chute, as shown in Fig. 11, is of such width that its sides 47 fit within the space between two of the cross ties t of the railway and it has 10 a vertical side 48 which is secured to the bar 49, adapted to rest upon the cross ties. The bottom, 50, of the chute is inclined from the surface of the roadbed, between the rails, toward the pit e, so that when the 15 car is spotted over the chute and dumped, the material will tend to flow through the chute into the pit. At the lower end of the chute is arranged a gate 51 which may be opened and closed by means of a screw-threaded rod 52, and immediately below the 20 gate is a feed roller 53 having radial vanes, and inclined downwardly from the roller is an extension 50' of the bottom of the chute, for delivering the material on to the buckets 54 of the elevator. The power for 25 operating the feed roller 53 is supplied by the motor 25. The shaft 22 (Figs. 6 and 7) which is driven by the motor, has a sprocket wheel 55 which is connected by 30 chain 56 to a sprocket wheel 57 on a shaft 58, which is journaled on the fixed section f of the elevator frame. The shaft 58 is provided with a sprocket wheel 59, and a chain 60, applied to this sprocket wheel, 35 engages a sprocket wheel 61 (Figs. 10 and 11) on the shaft 62 which carries the feed roller.

When the unloader is ready for transportation from place to place, the covers of the 40 bin are closed and the elevator is folded, as indicated in dotted lines in Fig. 1, and the reach bar is connected between the columns which support the bin. When brought to the place where material, such as broken or 45 crushed stone, is to be unloaded from the cars, the elevator is unfolded and its lower end extended into the pit, as shown in Fig. 1, and the chain 60 is connected to the sprocket on the feeder. The covers of the 50 bin are then raised, thus forming an upward extension to the bin and increasing its capacity. The car to be unloaded is spotted over the chute G and the material is dumped or shoveled into said chute and passes down 55 through the feeder. The gate above the feed roller is opened to allow the material to pass through to the feed roller as fast as the buckets on the elevator chain can carry off the material. This feeder, by removing the 60 material at the bottom of the chute and throwing it into the buckets, prevents clogging of the chute, which would otherwise be very apt to occur with such material as crushed stone. The material carried upward 65 by the elevator buckets falls into the bin and

the operation is continuous. The bin has storage capacity enough to fill a large motor truck. The trucks drive under the bin, between its supporting columns, and by opening the gates in the bottom of the bin, the 70 trucks may be quickly loaded. In this way, the loading of the trucks does not interfere with the continuous operation of unloading the car. For road building, the invention is found very serviceable, because it may be set 75 up in position beside the railroad track at any point where it is convenient to deliver the road material. If the pit is not already provided at the point where the road material is to be delivered from the cars, it is 80 merely necessary to dig a pit and make a suitable excavation between the adjacent ties into which the chute G may be readily inserted, and when the chute is in position and the feed roller geared to the motor, the un- 85 loading operation may commence.

What I claim is:

1. In a portable car unloading apparatus, a bin having supporting columns spaced apart to afford a driveway there-between, 90 wheels supporting said columns, and a folding elevator secured to said bin.

2. In a portable car unloading apparatus, a bin having supporting columns spaced apart to afford a driveway there-between, 95 wheels supporting said columns, a detachable reach for connecting the lower ends of said columns together, and a folding elevator secured to said bin.

3. In a portable car unloading apparatus, 100 a bin having a hopper bottom with a gate-controlled discharge opening and having upwardly opening doors hinged to its sides and ends, columns supporting said bin and spaced apart to afford a driveway there-between, 105 wheels supporting said columns, and a folding elevator secured to said bin.

4. In a portable car-unloading apparatus, a bin having supporting columns spaced apart to afford a driveway there-between 110 and wheels supporting said columns, an elevator comprising a frame having a central section secured to the bin, an upper section hinged to the upper part of the central section and adapted to fold over the bin, and a 115 lower section in sliding engagement with the central section and adapted to extend below the wheels, a bucket chain on said frame, and means for operating said chain.

5. In a portable car-unloading apparatus, 120 a bin having supporting columns spaced apart to afford a driveway there-between and wheels supporting said columns, an elevator comprising a frame having a central section secured to the bin, an upper section 125 hinged to the upper part of the central section and adapted to fold over the bin, and a lower section in sliding engagement with the central section and adapted to extend below the wheels, a bucket chain on said frame, 130

means for operating said chain, and windlasses on the central section for raising and lowering the upper and lower sections.

6. In a portable car unloading apparatus, a bin having wheeled supporting columns spaced apart to provide a driveway therebetween, an elevator secured to the bin and comprising a bucket chain, a chute for receiving the material to be unloaded from the car and delivering it to the bucket chain, a feeder at the outlet of said chute, and means for operating said feeder and bucket chain.

7. In a portable car unloading apparatus, a bin having wheeled supporting columns spaced apart to provide a driveway there- 15 between, an elevator secured to the bin and comprising a bucket chain, a chute adapted to fit between adjacent ties of a railway and having means at one end adapted to rest on the cross-ties, a feeder at the lower end of 20 the chute, and means for operating said bucket chain and feeder.

In testimony whereof I affix my signature.
J GROVE BROWN.
